(57) CLAIM

The ornamental design for a printer, as shown and described.

DESCRIPTION

FIG. 1 is a front view of a printer;
FIG. 2 is a rear view thereof;
FIG. 3 is a left-side view thereof; and
FIG. 4 is a right-side view thereof;
FIG. 5 is a top view thereof;
FIG. 6 is a bottom view thereof; and
FIG. 7 is an enlarged perspective view thereof.
The broken lines are for illustrative purposes only and form no part of the claimed design.
